UNITED STATES PATENT OFFICE.

OLIVER HOWARD GENTRY, OF ROCHESTER, NEW YORK.

ADJUSTABLE COAT AND HAT RACK.

1,270,936.

Specification of Letters Patent.

Patented July 2, 1918.

Application filed March 27, 1918. Serial No. 225,015.

To all whom it may concern:

Be it known that I, OLIVER H. GENTRY, a citizen of the United States, residing at Rochester, in the county of Monroe and 5 State of New York, have invented certain new and useful Improvements in Adjustable Coat and Hat Racks, of which the following is a specification.

This invention relates to furniture, and 10 more especially to hat and coat racks; and the object of the same is to produce an article of this kind intended to take the place of the ordinary tree but having features of adjustability whereby it may be stood in 15 an apartment and attached to the ceiling so that it cannot be knocked over. A further object is to improve the details of structure, as hereinafter more fully described and claimed, and as shown in the drawings, 20 wherein:

Figure 1 is a side elevation of this device complete, partly broken away,

Fig. 2 is a horizontal section on the line 2-2 of Fig. 1,

Fig. 3 is an enlarged vertical sectional detail, taken about on the line 3-3 of Fig. 1. The base 1 of this device may have any suitable ornamentation and configuration, and from it rise a plurality of upright 30 standards 2 connected at their upper end by a head piece 3 having at its center a loop 4. Through the latter is slidably mounted the upper member 5 of a post or pillar, its upper end by preference having a transverse 35 tongue 6 entering a notch 7 within a cap plate 8 secured beneath the ceiling as seen, or possibly resting against the ceiling when said upper member is moved or pressed upward by means to be described. The base 40 and headpiece are further connected by a pair of upright guide rods 9 disposed on opposite sides of the post and of course on opposite sides of the loop 4. While not so shown, there may be four standards and 45 guide rods, but I prefer two of each. The lower member 15 of the post alines with and preferably conforms in configuration to that of the upper member, and is herein shown as somewhat shorter. It has screw eyes 19 50 at its sides slidably mounted on said guide rods 9. Its upper end passes into a sleeve or collar 14 which is permanently attached as at 13 to the lower end of the upper member, and between the two members is interposed 55 a coiled expansive spring 12 for holding them normally distended as far as possible.

If the lower member should rest upon the base, the force of this spring would lift the upper member and engage it with the cap plate 8 so that the entire structure would 60 be held upright and prevented from being knocked over; but when the ceiling is higher than is illustrated in Fig. 1, it becomes necessary to raise the lower member 15 of the post before the spring comes into action, and 65 in raising the same the eyes 19 and guides 9 are useful although some means must be provided for holding the lower member in adjusted and elevated position.

The lower extremity of the lower member 70 is reduced and flattened to form a tongue 16, and secured to opposite sides thereof are the upper leaves 17 of two hinges, their lower leaves 18 being elongated laterally as best seen in Fig. 1 and passing astride the guide 75 rods 9 as best seen in Fig. 2. A bolt 19 having a winged nut 20 on its threaded end now connects the two leaves 18 at a point considerably below the tongue 16, and when this nut is set up tight it is obvious that these 80 leaves are drawn toward each other and their extremities are gripped upon the guide rods 9. Therefore when the device is to be adjusted to higher ceilings than as illustrated in Fig. 1, the two members of the 85 post are run up in the main frame, the upper member sliding through the loop 4 and the eyes 19 of the lower member traveling on the guides 9, and when they have reached their upper limit and the spring 12 has been 90 put under considerable tension, the wing nut 20 is set up to clamp the leaves 18 against the guides and to hold the parts in this position. Details of the features for supporting hats, coats, and other garments are 95 hardly necessary. I have shown pegs 21 on which hats may be hung. I have also shown arms 22 pivoted at 23 to the upper portion of the post 5 and adapted to carry coat hangers 24 and the like. These arms 100 may be raised by means of cords or ropes 25 attached to the arms at 26 and over pulleys 27 on the post and then downward to fasteners 28 on the standards 2 and within reach of an operator standing on the floor. 105 Therefore either arm may be let down, the coat on its hanger attached, and then the arm raised so that the garment is elevated off the floor and out of a position where it is struck by persons passing. In fact the arm 110 and the garment may be raised so high that the pegs 21 are disclosed and uncovered for

use in hanging other garments. Further details, as well as the proportions and materials of parts, are not necessary.

The foregoing description and the drawings have reference to what may be considered the preferred, or approved form of my invention. It is to be understood that I may make such changes in construction and arrangement and combination of parts, materials, dimensions, et cetera, as may prove expedient and fall within the scope of the appended claims.

What is claimed as new is:—

1. In a rack of the type described, the combination with a skeleton structure having within it a pair of upright guide rods, and a loop in its upper portion between said rods; of a two-part post whereof the upper member passes movably through said loop and the lower member has eyes slidably mounted on said guides, an expansive spring interposed between the adjacent ends of said members, and means for fastening the lower member to the guide rods after it has been raised.

2. In a rack of the type described, the combination with a skeleton structure having within it a pair of upright guide rods, and a loop in its upper portion between said rods; of a two-part post whereof the upper member passes movably through said loop and the lower member has eyes slidably mounted on said guides, an expansive spring interposed between the adjacent ends of said members, a collar secured to the upper member and inclosing the spring and the upper end of the lower member, and clamping means on the latter for engaging said guides after the lower member has been raised sufficiently to put the spring under tension.

3. In a rack of the type described, the combination with a base, and a pair of upright guides rising therefrom; of a two-part post whereof the upper member engages the ceiling and the lower member has eyes slidably mounted on said guides, an expansive spring interposed between said members, a collar secured to one member and inclosing the spring and the adjacent end of the other member, and clamping means on the lower member for engaging said rods after it has been raised sufficiently to put the spring under tension.

4. In a structure of the type described, the combination with a skeleton framework having upright guides, a post made in two parts whereof the uppermost is movable be-

tween said guides and above the structure and the lowermost is slidably mounted on said guides, an expansive spring between the contiguous ends of said members, and a housing inclosing the same; of a pair of hinges whose upper leaves are secured to the lower end of the lower members and whose lower leaves are elongated to pass astride said guides, and a clamp bolt through said lower leaves and having a winged nut on its threaded end, for the purpose set forth.

5. In a hat and coat rack, the combination with a base, upright standards rising therefrom, a head piece connecting them and having a loop, and guides connecting the head piece and base; of a two-part post whose upper member extends loosely through said loop and whose lower member is disposed beneath the upper member and guided on said guides, means for holding the lower member raised, the upper end of the upper member having a transverse tongue, and a cap plate adapted to contact with the ceiling and having a transverse notch engaged by said tongue.

6. In a garment hanger of the type described, the combination with a base, a skeleton structure thereon, a telescopic post, and means for projecting the upper member of the post above said structure into contact with the ceiling; of arms pivotally mounted on said post above said structure and having means for the attachment of coat racks, and lifting means attached to said arms and led downward to fasteners on the structure within reach of an operator on the floor, for the purpose set forth.

7. In a garment hanger of the type described, the combination with a skeleton structure, a post, and means for projecting the post above said structure into contact with the ceiling; of arms pivotally mounted on said post above said structure and having means for the attachment of coat racks, and lifting cords attached to said arms and led over pulleys on the post and downward to fasteners on the structure within reach of an operator on the floor, for the purpose set forth.

In testimony whereof I affix my signature in presence of two witnesses.

OLIVER HOWARD GENTRY.
